(57) **CLAIM**

The ornamental design for an plush toy with eyes and mouth, as shown and described.

DESCRIPTION

FIG. 1 is a perspective view of an plush toy with eyes and mouth showing a new design;

FIG. 2 is a front view thereof;

FIG. 3 is a back view thereof;

FIG. 4 is a side view thereof;

FIG. 5 is an opposite side view thereof;

FIG. 6 a top view thereof;

FIG. 7 is a bottom view thereof;

FIG. 8 is a perspective view of an plush toy with eyes and mouth showing a new design;

FIG. 9 is a front view thereof; and

FIG. 10 is a back view thereof;

FIG. 11 is a side view thereof;

FIG. 12 is an opposite side view thereof;

FIG. 13 a top view thereof; and,

FIG. 14 is a bottom view thereof.

The broken lines showing the plush toy with eyes and mouth are for the purpose of illustrating portions of the article that forms no part of the claimed design.

1 Claim, 8 Drawing Sheets
